EASEL

Elea E. Shaw, Cleveland, and Charles W. Chance,
Cleveland Heights, Ohio

Application July 12, 1932, Serial No. 622,120

5 Claims. (Cl. 35—60)

This invention relates to an easel and particularly to an easel especially adapted for use in the school room for combined instruction and game purposes, although, of course, the easel will have the same utility when used in the home and other places.

An object of the invention is to provide an easel which is so constructed that it may be used for the playing of a number of different games and for the giving of various forms or courses of instruction, either separately from the playing of the games or combined therewith as a part of the same.

Another object of the invention is to provide an easel of the character specified and one wherein means are provided for testing the aptitude or inaptitude of a child with respect to various mental activities, such as arithmetic, reading, and the like.

Another object is to provide an easel such as specified in the first mentioned object, which is of simple construction, is compact, can be readily changed to permit the playing of different games thereon or the use of the same for giving different forms of instruction, and which when folded up during non-use provides for the housing of all the parts.

Further and additional objects will become apparent during the detailed description that is to follow of an embodiment of the invention.

Referring to the accompanying drawings wherein said embodiment of the invention is illustrated:

Figure 1 is a perspective view of the easel showing the same in one of its many different positions of adjustment for accomplishing certain of its various purposes;

Fig. 2 is a perspective view showing the easel in a different position from that shown in Fig. 1;

Fig. 3 is a perspective view showing the easel in a still different position from those illustrated in Figs. 1 and 2 and for the accomplishment of a different purpose;

Fig. 4 is a perspective view showing the easel in the reverse position from that shown in Fig. 3 and one wherein a different game may be played thereon;

Fig. 5 is an elevational view of the easel in the position shown in Fig. 1, and looking directly at the same from one side thereof, the removable blackboard insert being omitted, however, in this view;

Fig. 6 is a sectional view taken substantially on line 6—6 of Fig. 5, looking in the direction of

the arrows, the removable blackboard insert being shown about to be placed upon the easel;

Fig. 7 is an elevational view of the easel looking directly at the same from the side opposite to that shown in Fig. 5;

Fig. 8 is an elevational view of the easel in the position shown in Fig. 3 and is taken looking directly at the same from the side thereof;

Fig. 9 is a vertical sectional view of the easel taken substantially upon the line 9—9 of Fig. 8;

Fig. 10 is an elevational view of the easel taken from the opposite side to that shown in Fig. 8, and

Fig. 11 is a sectional view taken substantially on line 11—11 of Fig. 10, looking in the direction of the arrows with the easel in the closed position.

The easel comprises pairs of leg members 20 and 21 of equal width and thickness hinged together at their upper ends by hinge pins or other suitable hinge members 22, with the legs of one pair on one side of the easel lying outwardly of

the legs of the other pair on the opposite side thereof. The pair of legs 20 and the pair of legs 21 have game boards 23 and 24 secured to the edges thereof, respectively, that are outermost when the easel is closed, wherefore, the

thickness of the easel in the closed position equals the width of one of the legs plus the thickness of the two game boards 23 and 24. The game boards 23 and 24 are of equal length and terminate flush with the outer sides of the outermost legs when

the easel is closed, that is, the ends of one of the game boards are flush with the sides of the legs to which it is attached, while the other game board extends outwardly of the sides of the legs to which it is attached a distance equal to the

thickness of the legs.

On the inner side of the board 23, and adjacent to, but slightly above its lower edge, there

is secured an outwardly extending ledge or shelf 25 of less length than the distance between the

legs to which the board 23 is secured and substantially of the same width as said legs, for a purpose

later to be explained.

The board 24 on its inner side is provided with an outwardly extending shelf or ledge 26 extending the full length between the inner sides of the legs to which the board is secured, said shelf or ledge being substantially the same width as the legs and being secured to the board with its lower side flush with the bottom edge thereof.

When the easel is folded the legs 21 fit between the ends of the ledge 25 and the inner sides of the legs 20, while the ledge 25 lies above and fits over the ledge 26, (see Fig. 11).

The board 23 is provided with a plurality of

openings 27, preferably of various geometrical configurations, suitable numbers or other indicia appearing on the board adjacent each opening on both sides of the board. The board 23 may 5 be used for a bean bag or similar game or it may be used in conjunction with said game for purposes of instruction.

On the inner side of the board 24 there is provided a layer of cork or other suitable material 28, adapted to take thumb tacks for holding drawing papers, notices or the like. On the outer side of the board 24 a plurality of hooks 29 are arranged preferably in vertical and horizontal rows and there may be suitable numbers or other 10 indicia upon the board adjacent each of the hooks. The outer side of the board 24 can be used for a ring toss or other similar game board or pictures and strips of paper bearing certain words, sentences, or numbers may be hung upon 15 the hooks or supported thereby.

It is also proposed to employ a removable part with the easel, which part may be termed an insert and comprises a rectangular frame 30 of a width a little less than the distance between the 20 innermost legs when the easel is closed and of a thickness a little less than the width of the legs, so that when the easel is folded this frame can be slid between the boards 23 and 24 and will rest upon the ledge 25, thus being completely 25 housed in the easel. The frame 30 carries a blackboard 31 and a sheet of cork or similar material 32, the blackboard and cork surfaces being accessible from opposite sides of the insert or frame, so that when it is desired to use the 30 one or the other it is merely necessary to reverse the frame.

When the easel is positioned, as shown in Fig. 1, the insert or frame 30 may be supported upon the ledge 25 with either the cork sheet or the 35 blackboard located at the outer side. If the cork sheet is outermost then drawings, paintings, charts, or notices may be secured thereto by suitable means, such as thumb tacks. When the insert is reversed and the blackboard side thereof positioned outermost, it can be put to all the general uses of a blackboard.

When the easel is in the position shown in Fig. 2, the cork layer 28 on the board 24 can be used for purposes similar to the cork sheet of the 40 frame 30, just above referred to.

When it is desired to use the easel with the outer side of the board 24 exposed, the legs 20 and 21 are merely swung around to a position 45 opposite to that shown in Figs. 1 and 2, that is they are moved to the position shown in Fig. 3. The board 24 may then be used for hook, ring toss, or other similar games, or various educational drills may be carried on by means of 50 phrases or instructions arranged on strips that are hung or positioned upon the hooks 29. When the easel is used for a ring toss, or other similar game, the game may also be extended into a course in arithmetic by means of the numbers located adjacent each of the hooks 29.

The easel may be turned around from the position shown in Fig. 3 to that shown in Fig. 4, in which position it can be used for a bean bag or similar game, since the openings in the board 23 are now exposed for that purpose. Also, instruction in arithmetic may be combined with the game, by placing numbers adjacent each of the 55 openings. It should also be noted that, when the easel is in the position shown in Fig. 1, the frame 30 may be removed and the board 23 immediately 60 used for the bean bag game.

Another feature of the easel is that when it is positioned, as shown in Fig. 3, a bean bag, or similar game and a ring toss, or similar game may be simultaneously played thereon from opposite sides of the easel.

It will be noted that the easel is so constructed that it is compact and that when it is folded the frame or insert 30 is conveniently received between the boards 23 and 24 and can be stored therein. Furthermore, the easel possesses the 10 advantage that the opposite sides of the boards 23 and 24 may be readily made available for a multiplicity of different purposes, a few of which were enumerated above.

Although a preferred embodiment of the invention has been illustrated and described herein, it will be understood that the invention is susceptible of various modifications and adaptations within the scope of the appended claims.

Having thus described our invention, we claim: 20

1. An easel comprising two pairs of legs pivotally connected together adjacent their upper ends and adapted to have their relative positions reversed, a board arranged on each pair of legs intermediate the ends thereof, said boards being secured to corresponding edges of the pairs of legs, and a ledge on the leg engaging side of one of said boards for supporting a removable member such as a blackboard. 25

2. An easel comprising two pairs of legs pivotally connected together adjacent their upper ends, a board arranged on each pair of legs intermediate the ends thereof, said boards being secured to corresponding edges of the pairs of legs, and a ledge on the leg engaging side of each board for supporting a removable member such as a blackboard, said ledges being arranged at different 30 heights to clear each other in the folded condition of the easel. 35

3. An easel comprising two pairs of legs pivotally connected together adjacent their upper ends, a board arranged on each pair of legs intermediate the ends thereof, said boards being secured to corresponding edges of the pairs of legs, a ledge secured to the leg engaging side of said first mentioned board and of a length such that its opposite ends are spaced from the inner sides of the legs slightly greater than the thickness of the legs, and a ledge secured to the leg engaging side of the second mentioned board, of a length 40 such that its opposite ends engage the inner sides of the legs, and at a height such as to clear said first named ledge. 45

4. In combination, an easel comprising two pairs of legs pivotally connected together adjacent their upper ends, a board arranged on each pair of legs intermediate the ends thereof, said boards being secured to corresponding edges of the pairs of legs, a ledge secured to the leg engaging side of said first mentioned board and of a length such that its opposite ends are spaced from the inner sides of the legs a distance slightly greater than the thickness of the legs, and a ledge secured to the leg engaging side of the second mentioned board at an elevation different from that of the first mentioned ledge and of a length such that its opposite ends engage the inner sides of the legs whereby when said easel is closed said first mentioned ledge will clear said last mentioned ledge and a compartment will be formed 55 between said boards, legs and upper ledge, and a removable member such as a blackboard adapted to fit within said compartment when the easel is closed and to be supported upon either of said ledges in certain open positions of said easel. 60

5. In combination, an easel comprising a pair of inner legs and a pair of outer legs, two aligned pivot pins at the top of the easel, each pin connecting one leg of each pair to one leg of the other 5 pair, a board attached to the legs of each pair, said boards being spaced apart when the easel is folded to bring the legs of the two pairs into register, a ledge supported upon the easel at the bottom of one of said boards substantially bridging the space between the boards when the easel is folded as aforesaid, said easel being adapted to be turned upon said pivots to a reverse position to expose the other sides of said boards, said ledge being adapted to support a separate board when the easel is folded together with the ledge inside, or when the legs are turned upon their pivots into the reversed position with the ledge outside. 5
